[57] CLAIM

The ornamental design for a wireless telephone, as shown and described.

DESCRIPTION

FIG. 1 is a perspective view of a first embodiment of a

wireless telephone showing our new design; FIG. 2 is a top plan view thereof; FIG. 3 is a left side elevational view thereof; FIG. 4 is a front elevational view thereof; FIG. 5 is a bottom plan view thereof; FIG. 6 is a right side elevational view thereof; FIG. 7 is a rear elevational view thereof; FIG. 8 is another left side elevational view thereof, wherein the ear piece portion is in the first position; and FIG. 9 is another left side elevational view thereof, wherein the ear piece portion is in the second position. FIG. 10 is a perspective view of a second embodiment of a wireless telephone showing our new design; FIG. 11 is a top plan view thereof; FIG. 12 is a left side elevational view thereof; FIG. 13 is a front elevational view thereof; FIG. 14 is a bottom plan view thereof; FIG. 15 is a right side elevational view thereof; FIG. 16 is a rear elevational view thereof; FIG. 17 is another left side elevational view thereof, wherein the ear piece portion is in the first position; and FIG. 18 is another left side elevational view thereof, wherein the ear piece portion is in the second position. FIG. 19 is a perspective view of a third embodiment of a wireless telephone showing our new design; FIG. 20 is a top plan view thereof; FIG. 21 is a left side elevational view thereof; FIG. 22 is a front elevational view thereof; FIG. 23 is a bottom plan view thereof; FIG. 24 is a right side elevational view thereof; FIG. 25 is a rear elevational view thereof; FIG. 26 is another left side elevational view thereof, wherein the ear piece portion is in the first position; and FIG. 27 is another left side elevational view thereof, wherein the ear piece portion is in the second position. FIG. 28 is a perspective view of a fourth embodiment of a wireless telephone showing our new design; FIG. 29 is a top plan view thereof; FIG. 30 is a left side elevational view thereof; FIG. 31 is a front elevational view thereof; FIG. 32 is a bottom plan view thereof; FIG. 33 is a right side elevational view thereof; FIG. 34 is a rear elevational view thereof; FIG. 35 is another left side elevational view thereof, wherein the ear piece portion is in the first position; and

FIG. 36 is another left side elevational view thereof, wherein the ear piece portion is in the second position.
